KEY MEANS FOR SHAFTS AND ROTORS AND
METHOD OF PRODUCING SAMENormand W. Morse, Chicago, Ill., assignor, by
mesne assignments, to Gray-Mills Corporation,
Evanston, Ill., a corporation of Illinois

Application October 9, 1943, Serial No. 505,650

11 Claims. (Cl. 287—53)

1

The present invention relates to key means for a shaft and rotor or the like.

Key means usually comprise axial channels or sockets in the shaft and in the rotor which extend axially and in which is usually disposed a key also extending axially. Regardless of the means that might be used to prevent axial relative movement of the shaft and rotor there is usually the danger of movement or loosening of the key in an axial direction. Another form is one wherein there is a transverse bore through both the rotor and the shaft, and a pin, as a cotter pin, extends through the bores, or a cross pin is driven into the bores. In all cases mentioned there is considerable work involved, which increases the cost of the resultant device, and in most instances the work must be done by the one assembling the machine at the time of such assembly, and not by the manufacturer.

The present invention comprehends a simple structure, which may be made by the manufacturer, at much reduced cost, and leaving nothing for the assembler to do but to merely tighten the parts, the shaft and the rotor, together, wherein a simple displacement or shearing of a part of the key element, which is a rigid part of the shaft, may be effected, to set or lock the remainder of the key element in the keyway.

Among the objects of the present invention is to provide a key means and a method of making the same in which the rotor may have a transverse, as diametric, keyway, as at an end of the rotor, and the shaft having a laterally extending, as radial, key element fitting into such keyway so as to lock the shaft and rotor together thereby, any suitable means being otherwise used, such as a thrust nut threaded to an end of the shaft, as at another end of the rotor, preferably at the side opposite from that where the key means is located.

Another object of the invention is to provide a keyway and a key element such that the key element will normally or initially have a segment thereof extending beyond a border of the keyway so that when the key element is effected into locked position the rotor will be forced against and displace such segmental portion of the key means whereby the remainder of the key element will be forced into and be locked into the keyway.

A further object is to provide the shaft with a clearance such as an annular channel provided in the shaft next to the key element so that as the segment is displaced the annular channel will act as a clearance space so as to afford such relative axial movement of the rotor and shaft

2

whereby the remainder of the key element will fit into the keyway.

Other objects, capabilities, advantages, process steps, features and the like are comprehended by the invention as will later appear and as are inherently possessed by the invention.

Referring briefly to the drawings:

Fig. 1 is a view in perspective of a device embodying the invention;

10 Figs. 2, 3 and 4 are axial sectional views of the same at different stages of assembly;

Fig. 5 is a transverse sectional view taken in a plane represented by line 5—5 in Fig. 4 of the drawings;

15 Fig. 6 is an axial sectional view of an alternative form of the invention;

Fig. 7 is an axial sectional view of another alternative form of the invention; and,

Fig. 8 is a transverse sectional view of the form shown in Fig. 7, and taken in a plane represented by line 8—8 in Fig. 7 of the drawings after the portion 14c has been sheared off.

Referring more in detail to the drawings, the embodiments chosen to illustrate the invention are shown as comprising a rotor 1 having a hub 2 and suitable radial rotor elements 3, the hub 2 having an axial bore 4; and a shaft 5 having a body portion 6, an integral reduced diameter portion 7 with a threaded end portion 8 which extends beyond the hub 2 for receiving a thrust nut 9 and a washer 10.

Referring to Figs. 1 to 5, inclusive, at an end of the hub 2 is provided a transverse, as diametrical, channel 11 constituting a keyway, the keyway having side walls 12 which may be tangent to the bore 4 extended or even more remote from the axis of the bore 4, that is, at a greater distance than the radius of the bore 4. The channel or keyway 11 may extend to the rim of the hub or may run short thereof, as being of a length equal to the diameter of the shaft body 6, or any other length intermediate the diameter of the bore 4 and the hub 2, as found convenient and desirable in manufacture.

45 Referring to Fig. 6 a similar keyway 11a is provided in an end of the hub 2 but it is deeper, as shown, to accommodate for the reception of a plurality of key elements 14 and 14a. In the form shown in Figs. 7 and 8 a similar keyway 11b is provided at an end of the hub 2, secantly relative to the axis of the shaft part 7, as shown.

The keyway 11b has a side wall 12a which may be diametric, as shown, but it may be at or along any transverse locus radially within the circumference of the key element 14.

At the juncture of the shaft segments 6 and 7 may be a shoulder 13 and axially spaced from the shoulder 13 and on the shaft portion 7 is an annular part or ring 14 from which is formed a key element to fit into the keyway 11, thus providing an annular channel 15 between the shoulder 13 and the ring 14. The latter is rigid with the shaft part 7, as integral therewith, and may be of a diameter equal to or greater than or less than the diameter of the shaft part 6, so long as it is initially greater than the width of the keyway 11, or extends beyond the wall 12 and over a part of the end of the hub 2. In the form shown in Fig. 6 there is a plurality of rings 14 and 14a spaced by annular channels 15 and 15a as shown, the depth of the keyway in this form being deeper than of the keyway shown in Figs. 1 to 4 inclusive. In the form shown in Figs. 7 and 8 the keyway 11b which has the transverse or diametric side wall 12a, is beneath a part 14b of the ring or key element 14, while the remainder 14c of the ring or key element 14 overlies the end of the hub 2 on the opposite side of the wall 12a, as clearly shown in particular in Fig. 7.

To form and set or lock the key element in the keyway, the nut 9 is turned to draw the shaft axially in the hub 2; downwardly as shown in the drawing. Figs. 2, 6 and 7 show the parts before the hub 2 is forced against the key element. The key element 14 or 14a extends across the width of the keyway 11 and has segmental parts 16 that overlap the end of the hub 2 adjacent the side walls 12 of the keyway 11. The key element 14 shown in Figs. 7 and 8, has its part 14b overhanging the side wall 12a and opposite the keyway 11b and its part 14c opposed to the end portion 16a of the hub 2 at the opposite side of the side wall 12a. As the nut is turned and tightened the end of the hub thrust against the said segment portion 16 or 14c will cause a displacement or shearing of the latter, Fig. 3 showing a part displacement or shearing of the segments 16, and a part entry of the remainder of the key element into the keyway 11. Further tightening of the nut 9 will further displace or shear the segment 16 or 14c so that the remainder of the key element 14 will fit and be locked into the keyway 11 or 11b, as shown in Figs. 4 and 5, and in Fig. 8. In the form shown in Fig. 6 the same function and result will be effected by the end of the hub 2 displacing or shearing segments successively from the key elements 14a and 14 so that the remaining portions of the key elements will fit and be locked in the deeper keyway 11.

In Fig. 8 the portion 14c of the key element 14 has been displaced or sheared off, as shown by a dotted line representation in Fig. 8, and the remainder 14b is in the keyway 11b and locked with the side wall 12a. The shoulder 13 may or may not be in contact with the end of the hub 2.

If the segments 16 or 14c be sheared off (see Fig. 5 or Fig. 8) the shaft may be drawn axially until the shoulder 13 abuts the end of the hub 2, but this is not necessary, so long as the key element is in the keyway. The key element may be in the keyway wholly or partly, that is, it may be entirely down in the keyway, as shown in Figs. 4 and 8, or only part way down, as shown in Fig. 3, and still be in locked condition. In the latter case the displaced segments may remain and may be abutted by the shoulder 13, yet this is not essential.

The term "displace" is herein used to com-

4
hend shearing, as to severance, or mere deforming.

While I have herein described and upon the drawings shown a few embodiments of the invention and the method of producing the same, it is to be understood that the invention is not limited thereto but may comprehend other constructions, details, arrangements of parts, process steps, features and the like, without departing from the spirit of the invention.

Having thus disclosed the invention, I claim:

1. A key means for a shaft and a rotor having a bore for receiving the shaft comprising the provision in the rotor of a keyway having a border disposed transversely to the axis of the rotor and shaft, a laterally extending key element rigid with said shaft and extending transversely of the keyway with a segment thereof extending beyond the border of the keyway and overlapping the rotor adjacent said border, and tightening means connected to said shaft and bearing against said rotor to force the rotor against said segment to displace it and force the remainder of the key element into said keyway in locked position therein and with said border.

2. A key means for a shaft and a rotor having a bore for receiving the shaft comprising the provision in an end of the rotor of a keyway having a border transversely disposed to the axis of the rotor and shaft, said shaft having a rigid key element extending laterally from said shaft and crosswise of said keyway and said border for fitting into said keyway adjacent said border to lock the rotor and the shaft from relative rotation, said shaft having a tightening means reacting against said rotor to hold said key element in locked position in said keyway and adjacent said border, said shaft having a transversely extending channel adjacent said key element at the side opposite from said rotor.

3. A key means for a shaft and a rotor having a bore for receiving the shaft comprising the provision in an end of the rotor of a keyway having a border transversely disposed to the axis of the rotor and shaft, said shaft having a rigid key element extending laterally from said shaft and crosswise of said keyway and said border for fitting into said keyway adjacent said border to lock the rotor and the shaft from relative rotation, said shaft being provided with a lateral recess adjacent said key element and on the opposite side of the key element from that of the rotor end.

4. A key means for a shaft and a rotor having a bore for receiving the shaft comprising the provision in an end of the rotor of a keyway having a border transversely disposed to the axis of the rotor and shaft, said shaft having a rigid key element extending radially from the shaft and fitting in said keyway adjacent said border to lock the rotor and the shaft from relative rotation, said shaft having an annular channel adjacent the key element at the side opposite from the rotor.

5. A key means for a shaft and a rotor having a bore for receiving the shaft comprising the provision in an end of the rotor of a keyway having a border transversely disposed to the axis of the rotor and shaft, said shaft having a rigid key element extending radially from the shaft and extending crosswise of the keyway with a segment of said key element extending beyond the border of the keyway and overlapping the rotor adjacent said border, said shaft having an annular channel adjacent the key element at the

side opposite from the rotor to afford a clearance for displacement of said segment, and tightening means connected to said shaft and bearing against said rotor to force the rotor against said segment to displace it and force the remainder of the key element into said keyway in locked position therein and adjacent said border.

6. A key means for a shaft and a rotor having a bore for receiving the shaft, comprising the provision in the rotor of a keyway disposed transversely to the axis thereof, said shaft having a reduced diameter portion for fitting axially in the bore of the rotor and having a shoulder at the juncture of the reduced diameter portion of the shaft and the remainder of the shaft, said reduced diameter portion having a rigid key element in axial spaced relation to said shoulder and extending radially, said key element being of a width to fit into said keyway.

7. The method of keying together two members such as a rotor and a shaft which comprises the steps of forming an annular wale concentric with the axis on one of the two members, of forming on the other member a recess normal to the member's axis and having at least one wall non-concentric with the periphery of the wale and spaced therefrom at one point by a distance radially from the member's axis which is less than the outside radius and equal to or greater than the inside radius of the annular wale, and of forcing said annular wale into said recess so that said wall will shear off a part of the annular wale to establish a locking engagement between the two parts.

8. The method of keying a rotor to a shaft which comprises the steps of forming an annular wale integrally on the shaft, of cutting a slot transversely of the rotor hub having a width less than the outside diameter and equal to or greater than the inside diameter of the annular wale, and of forcing the annular wale into the slot so that walls of the slot cut off portions of the annular wale.

9. The method of keying a rotor to a shaft which comprises the steps of reducing the diameter of the end of a shaft to receive the journal of the rotor, of cutting an annular channel in the shaft close to the reduced portion to form an annular wale, of cutting a channel having a

width less than the outside diameter and equal to or greater than the inside diameter of said annular wale across the hub of the rotor and the journal, and of forcing the transverse channel against the annular wale so as to shear off portions of the wale and establish a non-rotatable relationship between the rotor and the shaft.

10. The method of keying a rotor to a shaft which comprises the steps of reducing the diameter of the end of a shaft to receive the journal of the rotor, of cutting an annular channel in the shaft close to the reduced portion to form an annular wale, of cutting a channel having a width less than the outside diameter and equal to or greater than the inside diameter of said annular wale across the hub of the rotor and the journal, of threading the end of the shaft, of mounting the rotor on the reduced end of the shaft with the transverse channel abutting the annular wale, and of drawing a nut up on the threaded end portion against the rotor so as to cause the walls of the channel to shear interfering portions of the annular wale.

11. The method of keying together two members which comprises the steps of forming a wale around one member, of forming an opening in the other member having a configuration that will not register with the periphery of the wale and does intercept the periphery of the wale on the first member, and of forcing the opening in the second member onto the wale of the first member so as to shear portions of the wale and establish a non-rotatable relationship therebetween.
